UNITED STATES PATENT OFFICE

SIMON J. LONERGAN AND HOWARD E. GINTHER, OF LA PORTE, INDIANA, ASSIGNEES
TO BASTIAN-MORLEY CO., OF LA PORTE, INDIANA, A CORPORATION OF INDIANA

CONTROL MECHANISM

Application filed May 28, 1927. Serial No. 194,987.

This invention relates to a burner for a combustible fluid, more particularly to an improved means dependent on the burning or non-burning of a pilot jet or flame to control the fluid supply to the burner.

One object of the invention is to provide an improved valve operating mechanism and a control means therefor associated with the burner or a pilot therefor, whereby the combustible medium is cut off in the event the flame serving as a pilot goes out accidentally or otherwise.

Another object of the invention is to provide an improved valve mechanism under control of a pilot flame and capable of operating positively and quickly, whereby the inaction of the valve and its mechanism for a long period of time does not affect its action when the pilot flame goes out.

Another object of the invention is to associate with a fluid burner and the combustible fluid supply therefor, an improved thermostatically operated valve mechanism arranged to positively cut off the fluid supply in the event the pilot flame becomes extinguished.

Another object of the invention is to provide a thermostat mechanism for controlling the fluid supply to a burner and to associate with the thermo elements of such mechanism a suitable heat guard or spreader to prevent overheating of such elements.

Other objects of the invention will be apparent to those skilled in the art to which our invention relates from the following description taken in connection with the accompanying drawings, wherein

Fig. 1 is a vertical section of a fluid heater having a burner and a pilot and our improved mechanism associated with the latter for controlling the supply of combustible medium to the burner.

Fig. 2 is a fragmentary sectional view of parts shown in Fig. 1, enlarged.

Fig. 3 is a fragmentary section of the thermostat, valve operating mechanism and valve, the parts shown being similar to those shown in Fig. 2, but disposed in the position they occupy after the pilot is extinguished and the valve is closed.

Fig. 4 is a section on the line 4—4 of Fig. 3.

Fig. 5 is a section on the line 5—5 of Fig. 3.

Fig. 6 is a section on the line 6—6 of Fig. 3.

Fig. 7 is an end elevation of the parts shown in Fig. 3, looking towards the right.

Fig. 8 is a fragmentary view, partly in section, showing a slightly modified form of construction.

Fig. 9 is a front view of the parts shown in Fig. 8.

Fig. 10 is a fragmentary view, partly in section, showing another form of construction.

Fig. 11 is a sectional view, substantially similar to Fig. 3, but showing a different form of construction.

Fig. 12 is a section on the line 12—12 of Fig. 11.

Fig. 13 is a fragmentary view of a further modified form of construction.

Fig. 14 is a section on the line 14—14 of Fig. 13.

In the drawings, 1 indicates a burner for a suitable combustible medium such as oil or gas for illuminating or heating purposes.

In the illustrated adaptation of our invention, the burner 1 is constructed to burn natural or artificial gas supplied by conduit or pipe 2, preferably formed integrally with the walls of the burner 1. The burner 1 may be of any desired construction, that shown in the drawings having a plurality of jets on its upper face. The outer end of the conduit 2 is shaped to form a suitable mixing chamber 3 into which the gas is supplied. The chamber wall is provided with a bridge 3a on which a plate 5 is adjustably mounted to regulate the air supply in a well known manner. The bridge 3a is provided centrally with a hollow boss 3a' through which extends the nozzle 6 of a valve 7.

In the application of our invention herein chosen for illustration, the burner 1 is shown associated with a water heater 8 of the storage type wherein the water is heated to and maintained at approximately a predetermined temperature for heating or service purposes. In this form of construction the supply of gas is controlled by the temperature of the water in the heater through a suitable thermostat 9, so that when the

water in the container cools by radiation or by the use of the heated water and its replacement with cold water, the burner is supplied with gas and serves to heat the water to the desired temperature, whereupon the gas supply is cut off.

While our invention may be used in connection with any kind or type of fluid burner, whether it is used for lighting or heating purposes, we have used it most advantageously where the combustible fluid for the burner is automatically supplied and cut off from time to time, by the operation of a suitable control, such as a thermostat.

15 In some forms of construction, a by-pass around the thermostat and the valve actuated thereby is provided, so that a relatively low flame will burn from the burner to serve as a pilot therefor when the full gas supply is admitted thereto by the thermostat, and in other forms the by-pass leads to a separate pilot jet close to the burner. In the event the burner in the first mentioned form of construction or the pilot in 25 the second mentioned form of construction is extinguished, the thermostat upon the lowering of temperature of the fluid in the container, will open the valve controlled or actuated by it and allow the full supply of gas to flow to the burner, and as the pilot flame of the burner or pilot, as the case may be, is out, this gas will escape and be wasted and possibly result in an explosion and damage therefrom or fatal consequences to persons in the house in which the apparatus is installed. Our invention has for its purpose the cutting off of the entire gas supply to the burner, in the event the pilot flame in either of the forms of construction referred 35 to is extinguished to prevent waste and other resulting damage. In the illustrated arrangement, a separate pilot gas supply pipe 4 is associated with the burner 1, its jet 4a being arranged adjacent and slightly above one edge of the latter, to ignite the gas when admitted to the burner.

In the illustrated construction, the heater 8 comprises a suitable container 8a having a suitable insulation jacket 8b and a skirt 10 forming a fire chamber 10a in which the burner 1 is mounted. 11 indicates a suitable spreader mounted in the bottom of the container and in operative relation to the burner 1 and connected through the container bottom with the interior thereof. 11a is a suitable drain pipe. 12 indicates the water supply pipe and 13 indicates the discharge pipe leading to various points in a service or heating system. 14 indicates a flue preferably leading from the fire chamber 10a through the bottom and top walls of the container 8a.

The pipe 4 is connected to the gas supply pipe 15 above the main thermostat 9. The construction of the thermostat 9 is not illus-

trated, nor will it be necessary to describe it, as it may be of any desired construction, but it is preferably similar to and operates like the thermostat mechanism shown in Letters Patent No. 1,581,712 granted to Carl M. Yoder, so that when the temperature of the water in the container 8a of the heater 8 rises to or above the temperature at which the thermostat is set to operate, the valve (not shown) in the casing of the thermostat 9 will cut off the supply of gas to the burner 1; likewise, upon the fall in temperature of the water in the container 8a the thermostat 9 will open the valve and admit gas to the burner 1.

From the casing of the thermostat 9 the supply pipe 15 leads to and is connected with an inlet nipple or tubular portion 16 of a casing 17. The opposite wall of the casing 17 is provided with an outlet nipple 18 connected with the valve 7, preferably directly to its inlet branch 7a. As will be understood the thermostat casing, pipe 15, casing 17 and valve 7 constitute the gas supply means to the mixing chamber 3 and burner 1. The inner wall of the inlet nipple 16 is preferably provided with screw threads to permit the mounting therein of a pipe section 19. The upper end of the pipe section is connected to the adjacent end of the pipe 15 in any desired manner, for example by a union 20. The lower end of the pipe section 19 is tapered and ground to form a valve seat 21 with which a valve element 22 (preferably a ball) engages to close off the supply of gas and disengages to permit the gas to flow to the burner. The casing 17 is enlarged, as shown at 17a, to provide a suitable space therewithin for a linkage, indicated as an entirety 23, actuated upon by the thermostat elements 24, 25, to actuate the valve element 22. The thermostat elements, 24, 25, comprise a rod and a tube, respectively. In the form of construction shown in Figs. 1, 2 and 3, the valve element 22 is below its seat 21 and moves upwardly to engage therewith and close the valve; and the tube 25 is formed of a suitable metal (such as copper) which has a relatively high co-efficient of expansion and the rod 24 is formed of a material which has a substantially zero co-efficient of expansion. The outer ends of the thermostat elements are adjustably connected together in the manner to be later set forth, whereas the inner end of the tube 25 is fixedly mounted on the wall of the enlarged portion 17a and the inner end of the rod 24 operatively engages one of the levers of the linkage 23 to effect its movement in one direction or the other. The outer portion or end of the thermostat elements 24, 25, is associated with or disposed in the heat zone of the pilot flame 4a whereby the heat therefrom will affect these elements to maintain the valve 22 open. Under normal conditions, that is, with the pilot jet 4a lighted as shown

in Figs. 1 and 2, the tube is expanded and the rod 24 is moved thereby endwise toward the left (as viewed in Figs. 1, 2 and 3), thus releasing pressure on the linkage 23 and permitting it, due to its weight, the weight of the valve element 22 and pressure of the gas thereon, to swing downwardly and allowing the valve element 22 to disengage the valve seat 21, as shown in Fig. 2, and the gas to pass the valve to the burner 1. In the event the pilot flame becomes extinguished, by accident or otherwise, the contraction of the element 25 will effect movement of the rod 24, in the opposite direction and it in turn through the linkage 23 will move the valve element 22 against its seat 21, as shown in Figs. 3 and 4, and hence positively shut off the gas supply.

The inner end of the tube 25 is preferably mounted in the end wall 17' of the enlarged portion 17a of the casing, in the following manner, so that the inner end of the rod 24 may extend through an opening 26 formed in such wall for engagement with the linkage 23; the end wall 17' is thickened and the outer portion of the opening 26 is enlarged, as shown at 27. The bottom of the enlarged portion is inclined outwardly to form a conical surface 28, which may be suitably ground and the inner free end of the tube 25 is expanded or flared laterally so as to fit substantially face to face against the surface 28. The inner side wall of the enlarged portion 27 is provided with screw threads to receive a hollow plug 29. The inner end of the hollow plug has a conical end wall which fits against the flared walls of the tube 25, so that when the plug 29 is tightened it clamps the inner end of the tube 25 against the surface 28 and thus insures a liquid tight and rigid connection between the tube and casing wall.

The adjustable connection between the outer ends of the thermo-elements 24, 25, preferably comprises a plug 30 fixed in any desired manner in the end of the tube 25 and having a threaded opening 31 through it to receive the threaded portion 32 of the rod 24, and a locking nut 33.

The thermo-elements 24, 25, may be mounted in any position relative to the pilot jet whereby the heat of the latter will maintain the tube 25 in expanded condition, but by preference the gas supply pipe 4 extends slightly below and parallel to the tube 25 and the latter is arranged so that its outer end terminates in close proximity to the pilot jet 4a. In this arrangement (1) the thermo-elements do not obstruct the heat and products of combustion from the burner 1 and (2) provision is readily made for protecting the thermo-elements from undue heating which would affect their tensile strength and otherwise damage the metal. For this latter purpose I provide a guard device 34 which is so constructed and associated with the pilot

jet 4a that the flame therefrom cannot play on or contact with the metal of the tube 25. As a result the tube is heated by conduction by its contact directly or indirectly with such device or by radiation of heat therefrom. In one form the guard device 34 consists of a relatively thick brass disk 34a (see Figs. 3 and 7) having a diameter somewhat larger than that of the tube 25 and interposed between the nut 33 and outer end of the tube 25 and in contact with the hollow plug. The lower portion of the disk 34a is extended and formed with an opening 35 through which the pipe 4 extends. In this arrangement the pilot jet 4a is beyond the guard 34a and the latter guards the tube from the flame and excessive heat. By preference, the jet 4a extends far enough beyond the guard 34a to direct its flame on the nut 33, so that the guard 34a as well as the tube 25 is heated by conduction and radiation. In this latter arrangement, a relatively large wall area is provided to enable the excessive heat to quickly radiate and not effect overheating of the tube 25. To protect the outer end of the rod 24, the nut 33 may be closed on its outer side and thus form a cap for the rod end. The nut 33 removably secures the guard in position.

In another form of heat guard (see Figs. 8 and 9) the pilot jet may be disposed below the outer portion of the tube 25 and the lower portion of the guard is extended inwardly below the tube and its lateral portions, as shown at 34b. In this form of construction the extended portion 34b is substantially semi-circular in cross section and its inner end carries a depending wing 37 formed with an opening 37a through which the pilot pipe 4 extends.

In either form of guard device where it is found that the tube 25 is unduly heated, we may provide between it and the adjacent parts a wall of suitable insulation material 38, such as asbestos, which serves to retard heat conduction to the tube. This form of construction is shown in Fig. 10, the insulation wall 38 being shown between the inner face of the disk portion 34a' and the tube end and between the inwardly extended portion 34b and sides of the tube. The insulation wall 38 may be of any desired thickness. If desired, the heat retarding member 38 may be removed and another member of greater or lesser thickness or having a greater or lesser co-efficient of heat conductivity substituted.

Each guard device or member 34 herein shown is formed with an opening 39 through which the rod 24 extends and the nut 33 serves to removably secure the device in rigid position, and where the device is lined with insulation or heat retarding material it also permits the latter to be removed. Accordingly, either or both may be replaced by devices of a different thickness or formed of mate-

rial having a greater or lesser heat conductivity.

The linkage 23 is shown as comprising two links 23a, 23b (the former constituting a lever) having operative engagement with the walls of the casing 17 or 17a and pivotally connected together so that when their pivoted together portions are articulated about their respective points of engagement with the casing, and the outer end of the long arm 23a' of the link or lever 23a will swing through a relatively long arc. By mounting the valve element 22 on the free end of the arm 23a', slight movement of the links relative to each other will effectively control the valve element 22 with respect to its seat. The engagement of the lever 23a with the casing is provided by a transverse shaft 39' supported by the side walls of the casing portion 17a, this shaft serving to support the link 23a and also the link 23b, and the engagement of the latter link with the casing 17 is provided by an abutment 40. The abutment 40 preferably consists of a pin having a screw threaded portion fitted into a threaded opening 41 formed in the casing wall. The rod 40 may be rotated to adjust its free end to regulate the movement of the links and through them adjust the seating and unseating of the valve element 22. The inner end of the thermo-rod 24 is arranged to engage one of the links, preferably the link 23b, to cause their movement about the shaft 39' and abutment 40 and relative to each other. The shaft 39' preferably consists of two members 39a, 39b, threaded and removably mounted in aligned threaded openings 39a' formed in the side walls of the casing portion 17a (see Fig. 6). The inner end of the member 39a is formed with an axial opening 39c and the inner end of the member 39b is reduced to form a pivot 39b' which extends through an opening in the link 23a and into the opening 39c. As shown, the shoulder formed by the reduced pivot portion 39b' and the inner end of the member 39a engage the opposite sides of the link 23a, to maintain it in position and against lateral movement.

The construction of the linkage and its mounting in the casing herein shown by way of example is substantially similar to the construction described and claimed in Letters Patent No. 1,402,189 granted to M. W. Thomas. The connection between the inner end of the thermo-rod 24 and link 23b is preferably of the ball and socket type, that is, the rod end is rounded and the adjacent link 23b is formed with a spherical socket 42 into which the rounded rod end fits, this construction serving to connect these parts together and to support the inner end of the rod in concentric relation to the opening 26 and tube 25. No claim is made herein to this form of connection as it forms the subject-matter of a co-pending application Serial No. 78,886 filed

jointly by Simon J. Lonergan and Harold D. Eaton.

43 indicates as an entirety a mounting for the valve element 22 on the free end of the link arm 23a'. Of the mounting 43, 44 indicates a base having a central boss 44a forming an annular seat around the latter for the end convolution of a coiled spring 45. The base 44 is provided with a depending lug 46 which fits between bifurcations provided on the end of the arm 23a'. The lug 46 is pivoted on a cross pin 47 supported by the bifurcations. The spring 45 is interposed between the base 44 and valve element 22 and engages and supports the latter to move it toward and from its seat. The valve element 22 is guided vertically that is, axially of the valve seat 21, by ribs 50.

48 indicates a washer engaging the lower convolution of the spring 45 and engaged by the head of a screw 49 threaded into an opening in the boss 44a, these elements serving to connect the spring to the base. The spring convolution is not fixed to the base 44 by the washer 48, but is preferably loosely connected thereto so that its upper end may swing laterally on the base and thus permit it to more freely accommodate itself to the valve element 22, which is guided vertically to and from its seat 21 by the guide ribs 50, as the lever arm 23a' swings about its fulcrum or shaft 39'. The convolutions of the spring are shaped to form a substantially conical coil, so that its upper or enlarged end will form a receptacle to support the ball when unseated. By providing a spring between the lever arm 23a' and valve element 22, the movement of the arm about its pivot may continue, after seating of the valve, without danger of damage to the linkage 23, valve 22 or its seat 21, the valve is yieldingly maintained against its seat and it may be operated to shut off the gas in the first part of the movement of the lever arm 23a', thus insuring the closing of the valve relatively soon after the pilot becomes extinguished and saving of gas.

In the form of construction shown, the supply pipe 15 leads directly to the pipe 19 and the latter is in line with the valve element 22. If desired, provision may be made for protecting the valve element and its seat from foreign matter and the heavier ingredients contained in the gas so that they will not accumulate thereon and prevent the closing of the valve, for example, as shown in Figs. 11 to 14, inclusive. Referring to Figs. 11 and 12, the casing 17b is provided near its upper portion and below the inlet pipe 19' with an annular wall 17c having on its lower surface a collar 21' forming a suitable seat for the valve element 22'. Disposed above and in spaced relation to the wall 17c is a dome shaped member 17d which is connected to the casing 17b by lugs. The dome member

17d being interposed in the path of the gas flowing from the inlet or supply pipe to the valve opening, serves to collect on its surface those heavy ingredients which would otherwise have a tendency to accumulate on the valve element and prevent its effective closing.

In Figs. 13 and 14, that portion of the casing 17x between the boss 16x for the supply pipe (not shown) and valve seat 21x and valve element 22x is offset, as shown at 17x'. In this arrangement, a reservoir is provided in the path of the gas to permit the accumulation in said offset of these heavy ingredients or foreign matter so that the same will not flow to and lodge on the valve 22x and affect its seating. By preference, the wall 17x' is provided with an upstanding flange 17f which serves to prevent the flow of such material off of the wall 17x'. The lower portion of the casing 17x is preferably also offset to position the boss 18x for the gas connecting pipe (not shown) in line with the boss 16x. In the forms of construction just referred to, tendency of the heavy ingredients and foreign material in the gas clogging the valve and preventing seating of the valve element is materially reduced or eliminated.

From the foregoing description it will be seen that the control mechanism operates in a positive manner to close the valve element 22 against its seat and to release the valve therefrom, permitting its weight supplemented by the pressure of the gas to unseat it. As the operating mechanism acts in a positive manner on the valve element 22, it will be understood that even if the pilot burns for an indefinite period, perhaps for many months and longer without being extinguished (during which period of time the thermostat elements, the linkage 23 and valve element—the latter open—remain stationary), such mechanism will, upon the going out of the pilot flame, positively and quickly operate the valve and shut off the gas.

In the preferred forms of construction, as shown herein, the valve element is below its valve seat and the movement of the arm 23a' thrusts it positively against the seat, the spring serving as a yieldable member between the arm and valve element. As a result the longer the movement of the arm the greater the pressure of the valve element against the seat, so that in the event any material accumulates on the valve element the pressure on the valve will tend to displace it therefrom. To insure seating, the seat 21 may be tapered and ground to provide a substantially knife edge seat.

51 indicates a guard depending from the upper wall 17a' and straddling the lever arm 23a' at a point beyond its pivot, so that the gas flowing through the casing 17 will be directed away from the pivot 39' and thus reduce the tendency of heavy and foreign

materials in the gas to accumulate in the casing.

52 indicates a device for supplying air to the gas which is burned from the jet 4a. This device serves to mix air with the gas to support combustion and is so constructed that (1) the air is heated prior to mixing and (2) danger of back firing at the air inlet ports is eliminated. For convenience, the device 52 is shown in section in connection with one of the modified embodiments (Fig. 10), but it will be understood that the device shown in Figs. 1 and 2 is similarly constructed. Of the device 52, 53 indicates a plug or body member formed with openings in its opposite ends in aligned relation to receive the adjoining ends of the pipe sections 4', 4x. Between these pipe ends the body member is formed with a tapered opening 54 forming an injector leading centrally into the pipe section 4x. 55 indicates a plurality of air inlet ports formed in the pipe section 4x adjacent the injector opening 54. 56 indicates a wall surrounding the pipe section 4x and in spaced relation thereto and connected with the body member 53 at one end. The wall 56 extends longitudinally of the pipe section 4x and in concentric relation thereto to a point remote from the air inlet ports so that the air entering its open end will travel a relatively long distance before mixing with the gas. In the preferred construction the wall and plug 53 close the annular space around the pipe section on that side of the air inlet ports 55 remote from the pilot jet 4a and the wall extends to the other side of these ports or toward the pilot jet a relatively long distance.

In our construction it will be noted that the main thermostat mechanism 9 and the thermostat mechanism under control of the pilot flame are interposed in the gas supply pipe 15 but at different points and are operated independently of each other by different heated mediums.

To those skilled in the art to which our invention relates many changes in construction and widely differing embodiments and applications of our invention will suggest themselves without departing from the spirit and scope thereof. Our disclosures and the description herein are purely illustrative and are not intended to be in any sense limiting.

What we claim is:

1. In apparatus of the class described, the combination of a burner, a supply pipe for a combustible medium connected to said burner, means for providing a pilot flame for said burner, a thermostat mechanism interposed in said supply pipe and having thermo-elements disposed in the heat zone of the pilot flame, operating means operatively connected with one of said elements, and a valve actuated by said operating means for controlling the flow of the combustible medium

through said pipe, said valve having a downwardly facing seat and the valve element therefor being disposed between the seat and said operating means, whereby the latter forces the valve element against its seat when operated in a direction opposite to both gravity and the flow of the combustible medium.

2. In apparatus of the class described, the combination of a burner, a supply pipe for a combustible medium connected to said burner, means for providing a pilot flame for said burner, a thermostat mechanism interposed in said supply pipe and having thermo-elements disposed in the heat zone of the pilot flame, operating means operatively connected with one of said elements and the valve element of said valve to automatically close and open the latter, and heat guard comprising a plate fitting over the inner thermo-element and engaging the outer element and a device threaded on the inner element and clamped against said plate and serving to connect the thermo-elements and plate together.

3. In apparatus of the class described, the combination of a burner, a supply pipe for a combustible medium connected to said burner, means for providing a pilot flame for said burner, a thermostat mechanism interposed in said supply pipe and having thermo-elements disposed in the heat zone of the pilot flame, operating means operatively connected with one of said elements, a valve actuated by said operating means for controlling the flow of the combustible medium through said pipe, said valve having a downwardly facing seat and the valve element therefor being disposed beneath the seat and above said operating means, and a compression spring interposed between said operating means and said valve element to compensate for the movement of said operating means after the valve element is seated.

4. In apparatus of the class described, the combination of a burner, a supply pipe for a combustible medium connected to said burner, means for providing a pilot flame for said burner, a valve in said pipe, a thermostat mechanism having thermo-elements, a portion of said elements being disposed in the heat zone of the pilot flame, operating means operatively connected with one of said elements and the valve element of said valve to automatically close and open the latter, and a heat guard, said guard comprising a plate transversely of the outer ends of said elements in contact therewith and having portions extending radially beyond said elements.

5. In apparatus of the class described, the

combination of a burner, a supply pipe for a combustible medium connected to said burner, means for providing a pilot flame for said burner, a valve in said pipe, a thermostat mechanism comprising concentrically arranged thermo-elements having their inner ends disposed in the heat zone of the pilot flame, operating means operatively connected with one of said elements and the valve element of said valve to automatically close and open the latter, and heat guard comprising a plate fitting over the inner thermo-element and engaging the outer element and a device threaded on the inner element and clamped against said plate and serving to connect the thermo-elements and plate together.

6. In apparatus of the class described, the combination of a burner, a supply pipe for a combustible medium connected to said burner, means for providing a pilot flame for said burner, a valve in said pipe, thermostat elements arranged concentrically and having their inner ends disposed in the heat zone of the pilot flame, operating means operatively connected with one of said elements and the valve element of said valve to automatically open and close the latter, and a heat guard carried by the inner ends of said thermo-elements, said guard comprising a device mounted on the inner end of the outer element and having a portion bent back below the lower side thereof.

7. In apparatus of the class described, the combination of a burner, a supply pipe for a combustible medium connected to said burner, means for providing a pilot flame for said burner, a thermostat mechanism interposed in said supply pipe and having thermo-elements disposed in the heat zone of the pilot flame, and comprising a tube connected at its inner end to the casing of said mechanism and a rod extending through said tube and having its outer portion connected to said tube, an operating means operatively connected to the inner end of said rod and a valve actuated by said operating means for controlling the flow of the combustible medium through said pipe, and heat guard means on the outer ends of said elements, said guard means comprising a transverse plate on said rod in engagement with the outer end of the tube and a nut enclosing the free end of the rod and engaging said plate.

In testimony whereof, we have hereunto subscribed our names.

SIMON J. LONERGAN.
HOWARD E. GINTHER.
